APPARATUS FOR BANDING ARTICLES

Thomas S. Bauman, Hialeah, Fla., assignor to Dominion Glass Company Limited, Montreal, Quebec, Canada

Application June 18, 1956, Serial No. 592,172

23 Claims. (Cl. 118—219)

This invention relates to improvements in the method of applying bands of ceramic paint to glass, pottery or similar articles and more particularly to improvements in multiple head ceramic banding machines whereby banding in various colours and width of bands can be accomplished in a single operation without removing the article from the machine.

The invention consists essentially in the provision of a multiple head rotating machine in which the width and spacing of the applied ceramic bands on the work piece are controlled by means of co-ordinated drives, cams and valves whereby the work and the ceramic applicator are brought into contact in a pre-arranged manner so that bands of various colour, width of spacing between bands, and width of bands can be applied from the co-ordination of one head with the work piece or the co-ordination of various heads with the work-piece, all in timed relation so that a minimum of ceramic paint will be applied at an even depth to the work at a speed which will ensure even application without throw-off or dripping of the ceramic paint as the work piece progresses, through the cycle of the machine.

The invention hereinafter described has the advantage over other machines for the same class of work in that it permits the application of multi-colour banding without the removal of the tumblers from chuck to chuck during the operation, in other words, the tumbler remains on the chuck as it is originally applied and all colours are put on the tumbler before it is taken off the chuck.

The object of the invention is therefore to provide a machine in which bands or designs may be quickly applied in one or more colours by a plurality of successive applications of the decorating material without removing the work piece or article being decorated, from the machine before the cycle of operation is complete.

A further object of the invention is to provide means for intermittently rotating the work holding carriage in timed relation to the raising and lowering of the ceramic paint applying mechanism.

A further object of the invention is to provide means for reciprocating the ceramic paint applying mechanism in timed relation to the setting of the work holding carriage to effect the application of bands of ceramic paint of various widths.

A further object of the invention is to provide suction means controlled by the rotation of the machine whereby the work is held securely to the head during a predetermined cycle of operation.

A further object of the invention is to provide an improved suction chuck whereby the work is held rigid on its work head during the complete cycle of operation.

These and other objects will be apparent from the following detailed specification and the drawings forming a part thereof, in which

Fig. 1 is a vertical sectional view of the banding machine showing the drives to the various operating mechanisms.

Fig. 2 is a sectional plan view taken on the line 2—2

of Fig. 1 and showing the input drive to the machine and also showing three output drives leading to the applicator raising and lowering mechanism and also showing a mounting bracket fitted to the side of the machine.

Fig. 3 is a sectional plan view taken on the line 3—3 of Fig. 1 showing the vacuum control valve raising cam and the work piece head raising or tilting cam.

Fig. 4 is a sectional plan view taken on the line 4—4 of Fig. 1 showing the vacuum chamber head plate with one of the work piece heads mounted on its supporting brackets and showing the pipe connections from the work head to the common vacuum chamber.

Fig. 5 is a sectional plan view taken on the line 5—5 of Fig. 1 showing the Geneva drive controlling the intermittent rotation of the vacuum chamber head plate shown in Fig. 4 with the Geneva wheel in one of the stationary positions.

Fig. 6 is a sectional plan view similar to Fig. 5 but showing the Geneva wheel partly rotated between one stationary position and another, and showing the Geneva crank in section to show the crank block in engagement with the wheel.

Fig. 7 is an enlarged front elevation of one of the applicator raising and lowering heads.

Fig. 8 is a sectional plan view taken on the line 8—8 of Fig. 7 showing the springs connected to the reciprocating bracket of the raising and lowering head to hold the bracket against the cam transmitting motion to the bracket.

Fig. 9 is a face view of the applicator reciprocating cam.

Fig. 10 is a side view of the cam shown in Fig. 9.

Fig. 11 is a partial plan view of the top of the applicator head showing a pair of ceramic paint applicators.

Fig. 12 is an enlarged sectional view of one of the work head suction control valves.

Fig. 13 is an enlarged sectional detail of one of the vacuum chucks shown in the free position without a work piece and with the suction line blocked off.

Fig. 14 is a fragmentary detail section of the cams shown in Fig. 3.

Fig. 15 is a sectional detail of the adjustable stop for the work-head.

Fig. 16 is an enlarged view of the work-piece mounted on its chuck and the paint applicator in contact with it and also showing in dotted lines the position of the applicator at the other end of its reciprocated travel to apply the width of band shown in the work piece.

Fig. 17 shows a curved surface work piece having two widths of banding applied at spaced intervals.

Fig. 18 shows another form of work piece having an extra wide band as would be applied at two stages on the machine.

Figure 19 is a partial view taken from Figure 1 showing the cam means holding one working head out of engagement with the friction disc.

Referring to the drawings, the machine is built on and around a central box casting 1 which in turn is mounted on a base 2 suitably supported by legs or other means not shown.

The machine is composed of four main parts, all operated from a common input drive shaft 3 which can be connected to any suitable source of power. These main parts are the work-piece heads A, the applicator heads B, the common suction head C and the Geneva drive D.

In the assembly of the machine illustrated and described the interconnection of the various parts are one form only in which the ultimate function of the machine can be achieved. Different forms of drives between the various parts could be utilized to achieve the same results, also the number of operative heads on the machine described could be increased or decreased and still be within the scope of the invention.

From the input drive shaft 3, which is connected to any suitable source of power, one drive branch is directed to the worm 4 and worm wheel 5 contained in the worm gear casing 6. The shaft 7, to which the worm gear 5 is keyed, passes down through the base 2 and carries on its lower end the drive sprocket 8. From the drive sprocket 8, the drive is carried through the chain or belt 9 to the sprocket 10 mounted on the lower end of the shaft 11 to rotate the friction drive plate 12 which is mounted on the upper end of the shaft 11 and which can be adjusted up or down thereon by means of the nuts 13.

The Geneva drive originates with the shaft 7 and is contained within the base 2. The Geneva crank 14 is keyed to the shaft 7 and engages with the Geneva wheel 15 to drive the wheel in intermittent steps corresponding in number to the number of work-piece heads A on the machine. The Geneva crank 14 is formed of upper and lower arms 16 supporting between them the arcuate face 17 which is concentric with the shaft 7, and also the pin 18 at the opposite end of the arms. The crank block 19 is rotatably mounted on the pin 18 between the crank arms 16. The Geneva wheel 15 is keyed to the sleeve shaft 20 and has a series of arcuate faces 21 on its outer periphery. These arcuate faces 21 are concentric with the arcuate face 17 of the crank 14 when the wheel is rotated by the crank into the position shown in Fig. 5 of the drawings. Slots 22 radiate inwards from the periphery of the Geneva wheel 15 and are spaced equidistant between the centres of the arcuate faces 21. The crank block 19, on rotation of the crank 14 engages with one of the slots 22 to rotate the wheel 15 for a portion of a revolution equal to the angle between the slots and between the arcuate faces 21 on the wheel. In this particular case the number of slots 22 is eight which is equal to the number of work-piece heads A. The length of the arcuate face 17 of the crank 14 is such that it just clears the outer periphery of the wheel 15 as the wheel is rotated between the arms of the crank when the block 19 is in engagement with one of the slots 22. The number of work-piece heads A and corresponding slots 22 in the Geneva wheel 15 can be varied to suit the overall size of the machine and the size and type of articles to be banded on it.

Mounted on the upper end of the sleeve shaft 20 is the common suction head C formed of the ring casting 23 and which with the cover plate 24 of the box casting 1 form a sealed chamber 25. As the cover plate 24 is stationary while the ring casting 23 rotates with the sleeve shaft 20, effective sealing between these two items is by means of the packing rings 26 set in annular recesses in the flange 27 of the ring casting 23 and in the top face 28 of the cover plate 24.

The cover plate 24 carries the arcuate cams 29 and 30 on its upper face, the outer cam 29 controlling the engagement and disengagement of the work-piece head A with the drive plate 12, while the inner cam 30 controls the operation of the valves in the vacuum lines from the common suction head C to the work-piece heads A.

The cams 29 and 30 are set in arcuate channels 31 and 32 on the surface of the cover plate 24 and are held in their adjusted annular position by means of the set screws 33.

The common suction head chamber 25 is connected with a source of vacuum by means of the pipe connection 34 secured through the cover plate 24.

The ring casting 23 has an extended flange 35 in which are mounted the vacuum controlling valves and the plungers controlling the engagement of the work-piece heads A with the drive plate 12. These valves are equal in number to the number of work-piece heads on the machine and consist of a series of cylinders 36, formed in the side of the suction head chamber 25. Each cylinder 36 is provided with a sleeve valve 37 having an

extension rod 38 projecting down through the bottom of the cylinder 36, the rod having a rounded end adapted to make smooth contact with the top surface of the inner cam 30. The cylinders 36 are provided with a cap 36 held down by the screws 40 and is provided with a screwed outlet 41 communicating with the interior of the cylinder 36 through the bore 42. The sleeve valve 37 is hollow to receive the compression spring 142 which is also seated in the cap 39. The cylinder 36 is provided with a port 43 communicating with the interior of the suction chamber 25 and has an exhaust port 44 open to the atmosphere. The sleeve valve 37 is provided with the ports 45-46. The spring 142 normally holds the sleeve valve 37 in the down position so that the ports 43 and 45 communicate with each other leaving the vacuum line open to the work-piece head A. However, when the valve 37 is lifted up by contact of the rod 38 with the cam 30, the port 43 is blocked off and the port 46 is brought into line with the exhaust port 44. In this position of the valve 37 the vacuum line to the work-piece head A is open to the atmosphere.

The work-piece heads A, eight in number, each consist of a cylinder 47 pivoted at 48 between the brackets 49 which, in turn, are secured to the top of the extension flange 35 of the ring casting 23. The brackets 49 hold the work-head piece assemblies A on an axis passing through the axis of the shaft 11 and the axis of the valves 37. Journalled in the cylinders 47 are the shafts 50, the inner end of which carry the contact roller 51 which frictionally engages with the under side of the drive plate 12 to effect rotation of the shaft 50. The outer end of the shaft 50 extending from the cylinder 47 is reduced in diameter to provide a seat 52 against which the disc 53 is seated. The outer end of the shaft 50 is counter-bored at 54 into which the extension or valve shaft 55 is fitted and permanently secured. The shafts 50 and 55 have a communicating axial bore 56 extending from the transverse bore 57 of the shaft and located within the cylinder 47 to the transverse bore 58 at the outer end of the shaft immediately adjacent to the end disc 59. A valve sleeve 60 is slidably mounted on the valve shaft 55 and has secured to it the friction chuck disc 61. A similar sleeve 62 and friction chuck disc 63 is also slidably mounted on the shaft 55 and are separated by the compression spring 64. Both friction chuck discs have their outer peripheries rounded for ease of engaging and disengaging the work piece 65.

Mounted on the outer face of the disc 53 is a sealing disc 66 of relatively soft material against which the rim of the work piece 65 is pressed against and held by suction. A compression spring 67 is located between the chuck disc 63 and the washer 68, the latter protecting the sealing disc 66 from damage. The springs 64 and 67 normally hold the valve sleeve 60 against the end disc 59 to seal the transverse bore 58 and block the suction line 56.

The chuck discs 61 and 63 are of such a diameter that, when the work piece 65 is pushed over them, the internal surface of the work piece will frictionally engage with them and force them inwards against the pressure of the springs 64 and 67 thereby clearing the transverse bore 58 so that when the work piece rim contacts the sealing disc 66 the air is evacuated from the interior of the work piece and it is held firmly in the chuck until such time as the vacuum line is closed by the action of the valve 37. The spring 67 exerts very little back pressure on the chuck disc 63 so that leakage between the periphery of the disc 63 and the internal surface of the work piece 65 ensures complete evacuation of air from the work piece.

The vacuum line between the cylinders 47 and the common suction chamber 25 is completed by the flexible pipe 69 joining the cylinders 47 at 70 and the valve caps

39 at the screwed outlet 41, the flexible pipe allowing for the pivoting of the complete work-piece heads A.

In order to engage and disengage the contact roller 51 from the drive wheel 12 plunger, rods 71 are mounted in the extension flange 35 immediately below the outer end of each cylinder 47. These plunger rods 71 are provided with rollers 72 which make contact with the top surface of the cam 29 as the ring casting 23 is rotated from one station to another by the Geneva drive. The rising plunger makes contact with the under side of the cylinder 47 rotating it slightly on its pivot 48 against the action of the spring 73. Such pivoting of the cylinder disengages the roller 51 from the drive wheel 12 and stops rotation of the shaft 50. Stops 74 located on the extension flange 35 between the valve caps 39 and the plunger rods 71 are adjustable to hold the under side of the work piece 65 on a level plane independent of the plunger rod 71 when the roller 72 is out of contact with the cam 29 and the banding operation is being carried out.

The period of rotation of the work piece 65 on its chuck as the work piece head A is rotated from one station to another by the Geneva drive D is governed by the arcuate length of the cam 29 and its setting on the cover plate 24. Similarly, the arcuate length of the cam 30 and its setting on the cover plate 24 governs the period in which vacuum is cut off from the cylinder 47. As will be seen from Figs 2 and 3 of the drawings, rotation of the work-piece heads A is effected at each of the stations (a) at which banding operations can be carried out whereas vacuum will hold the work-piece on its chuck at all of these stations (a) plus the stations (b). The arcuate length of the cams 29 and 30 and their annular relationship to each other can be modified for any variety of production requirements.

The ceramic paint applicator is controlled to give vertical movement of the applicator to bring it into contact with the work piece 65 and to give horizontal movement of the applicator to control the width of the ceramic paint band on the work piece.

Describing first the drive giving vertical movement to the applicator. From the incoming drive shaft 3 sprocket 75 transmits drive through a chain 76 to the sprocket 77 mounted on the shaft 78. The shaft 78 is journaled in the bracket 79 which in turn is mounted on one of the machined mounting faces 80 on the side of the box casting 1. A bevel gear pinion 81 is keyed to the inner end of the shaft 78 and engages with the bevel gear 82. This bevel gear 82 is keyed to the sleeve shaft 84 journaled about the sleeve shaft 20 and is concentric with the shaft 11.

The box casting 1 is provided with eight machined mounting faces 80 set out at 45° intervals about the periphery of the casting. An applicator work head can be mounted on each of the remaining seven faces 80 or a head can be mounted on only some of these seven faces depending upon the type of work to be banded and the production volume desired of the machine.

In Fig. 2 of the drawings, the input drive to the bevel gear 82 is shown together with three output drives for connection to applicator work heads. Each of these output drives consist of a bevel pinion 85 keyed to the shaft 86 and in toothed engagement with the bevel gear 82. The shaft 86 is journaled in the top end of the bracket 87 which in turn is mounted on one of the machined faces 80. The bracket 87 also carries the shaft 88 journaled in its lower portion, the two shafts 86 and 88 being drivably connected together by the gear pinion 89 keyed to the outer end of the shaft 86 and the gear wheel 90 keyed to the shaft 88. The shaft 88 is held against lateral movement in the bracket 87 by the collar 91 attached to the inner end of the shaft.

Splined to the shaft 88 is the extension shaft 92 which is journaled in the bracket 93. This bracket 93 has the side flanges 94 adapted to slidably engage with the guide plates 95 mounted on the stationary bracket 96. The

brackets 96 are mounted on the sides of the base 2 directly under and centered with the output drives from the bevel gear 82. The bracket 93 is reciprocated on the bracket 96 by means of the cam 97 which is keyed to the shaft 88 and rotates therewith. The cam face 98 of the cam 97 makes contact with the roller 99 mounted on the pin 100 secured to the underside of the bracket 93. The travel imparted to the bracket 93 is controlled by the rise of the cam face 98 indicated at 101 in Fig. 10. The outward travel of the bracket 93 is against the effort of springs 102 which hold the bracket, through the roller 99 against the cam face 98 during all stages of reciprocating motion. The springs 102 are anchored to the bracket 93 by the pins 103 and to the bracket 96 by the pins 104.

Vertical movement of the applicator is obtained by means of the cams 105 and 106 which are adjustable with relation to each other to vary the time of lift of the applicator. The cam 105 is rigidly secured to the extension shaft 92 while the cam 106 is rotatably mounted on the shaft 92 radially with respect to the cam 105 and is secured thereto in any adjusted position by means of the pin 107 passing through the radial slot 108 in the cam 106 and threaded into the cam 105. Both cams 105 and 106 have cam lift surfaces 109 of the same radius, however the radial length of the surface 109 varies with the setting of the cams with respect to each other.

The applicator table 110 has a vertical member 111 sliding on the outer face 12 of the bracket 93 and held thereagainst by the keeper plates 113 which in turn are secured to the bracket 93 by the bolts 114.

A roller 115 is mounted on the pin 116 and is secured to the lower end of the vertical member 111 by means of the clamp plate 117. The roller 115 is held by gravity on the cam face of the cams 105 and 106, therefore, as the cams 105 and 106 are rotated by the shaft 92, the applicator table 110 is raised and lowered. The applicator table 110 is of channel section, the sides 118 of which support the applicator wheel assembly.

40 The applicator wheel 119 is journaled by the pin 121 in the forked end of the arm 120 which is pivoted in the bracket 122 by the pivot pin 123. The bracket 122 is forked at its lower to fit on the side member 118 of the applicator table 110 and is held in place thereon by the clamp screw 124. A stud 125 is pivotally mounted at 126 on the bracket 122 and passes through the boss 127 on the outer extension of the arm 120. A spring 128 is held in compression about the stud 125 between the boss 127 and the adjustable stop nut 129. A stop nut 130 on the stud 125 behind the boss 127 limits the upward movement of the applicator wheel 119 while downward movement of the wheel 119 is restrained by the spring 128. Adjustment of the tension on the spring 128 by the stop nut 129 controls the pressure of the applicator wheel 119 against the surface of the work piece 65 when the applicator table 110 is raised by rotation of the cams 105 and 106.

The ceramic paint 131 is contained in the pan 132 supported on the applicator table 110 by the bracket 133 and held secure thereon by the bolts 134. In Fig. 11 two applicator assemblies are shown mounted on the table 110. Any number of these applicator assemblies can be mounted side by side on the table 110, depending on the length of the work piece 65 and the number 65 of different colours to be applied to the work piece. The pans 132 can all contain the same colour of paint or each contain different colours. During normal working of the machine the applicator wheel 119 can be released from contact with the work piece 65 by depressing the lever 135 projecting from the bracket 120 adjacent the wheel 119.

In Figs. 1 and 16 a straight sided work piece or tumbler 65 is shown mounted on the chuck. With such a straight sided work piece it is desirable that the under side of the work piece be adjusted to a horizontal level. This en-

sures ease of travel of the applicator disc 119 along the surface of the rotating work piece to apply the band of paint 136. The width of the band of paint is controlled by that part of the horizontal stroke of the applicator in the direction of the arrows 137 as controlled by the cam 97, during the time in which the applicator is at the highest point of its elevation in the direction of the arrows 138 as controlled by the cams 105 and 106.

The width of band 136 as shown in Fig. 16 could represent the maximum width applied at any one applicator station on the machine while the bands 139 shown in Figs. 17 and 18 could represent the narrowest bands, these being varied in width by the use of discs 119 having different width of edges. The band 140 shown in Fig. 18 is of double the width of the band 136 and is obtained by first banding with a band as 136 at one applicator station and banding with another band 136 at the following station on the machine. The applicators at each station being set on the tables 110 so that the second applicator will commence to apply its band against the edge of the first band without forming a ridge of paint or leaving a gap between the bands. This is accomplished by the fine setting of the applicators possible and by the disc 119 selected for the job.

In the operation of this invention, the machine is set up to suit a production run of one form of work piece 65. If the work pieces 65 are tumblers as shown in the drawings, chuck discs 61 and 63 of suitable diameter to frictionally engage with the interior surface of the tumbler are fitted to the chuck and are moved inwardly on the shaft 55 by the work piece to expose the transverse opening 58 before the rim of the tumbler engages with the seal ring 66. If necessary, the seal ring 66 can be changed to suit the rim diameter of the tumbler 65. The necessary number of applicator work heads are assembled on the brackets 96 together with suitable cams 97 to give the desired horizontal travel of these work heads. Paint pans 132 and applicator disc assemblies are now mounted on each of the applicator tables 110 and spaced to give the desired pattern of banding on the work piece or tumbler 65. The stops 74 are now adjusted to tilt the cylinders 47 and with it the shafts 50 to a position which will bring the under side of the tumbler 65 to a horizontal position parallel with the horizontal travel of the applicator tables 110, as shown in Fig. 1 of the drawings. Further adjustment between the applicator and the tumbler 65 is possible by replacing the friction drive disc 51 by one having a smaller or larger diameter. Such additional adjustment may be necessary, in combination with the stop 74 when the tumbler 65 has a steep taper to its side or to suit a work piece whose side is contoured as in a vase. The cams 105 and 106 are now adjusted relative to each other to give the desired contact time between the applicator discs 119 and the work pieces 65. This contact time, combined with the horizontal travel of the applicator work head produced by the cam 97 fixes the width of paint band applied to the surface of the work piece.

The cams 29 and 30 are now adjusted relative to the applicator work heads. The cam 29 is set to a position which will allow the friction disc 51 to contact the drive plate 12 just before, during and after the work heads A are rotated into position over the various applicator work heads that have been set up on the machine. With such a setting the shafts 50 will be rotated and with them the work pieces 65 and, when the applicator discs 119 are raised into contact with the work pieces by the action of the cams 105 and 106, the applicator discs 119 will be rotated through friction contact with the work piece and will pick up paint from the pan 132 and deposit the paint on the surface of the work piece 65.

The setting of the cam 30 in relation to the applicator work heads is such that the valve 37 remains open for a relatively long period of the revolution of the machine allowing vacuum to be applied to each of the work piece

heads A to hold the work pieces 65 in their chuck before making contact with the first applicator disc 119 and to remain on the chuck as long as possible after passing over the last applicator disc 119. This allows the operator ample time to fit the work piece 65 on its chuck and remove it from the chuck without interference with the banding operation. Any additional time element allowed after the work passes over the last of the applicator discs 119 is usually sufficient to allow the paint to dry on the work pieces to allow handling necessary for removal of the work pieces from its chuck when the vacuum has been shut off at the valve 37.

In operation, the machine is constantly running and it is only necessary to feed work pieces on to the chucks as fast as the work heads A are rotated into place by the operation of the Geneva drive D.

In the actual application of the paint 131 to the work pieces 65, the width of the edge of the applicator disc 119, the speed of rotation of the work piece 65 while in contact with the applicator disc 119 and the timing of the reciprocation of the applicator work head, all combine to control the width of the applied band of paint, the depth of paint film and the smoothness of finish. The latter, is of great importance when it is realized that in fact the paint is applied to the work piece in the form of a spiral, but when the timing between rotation of the work piece and reciprocation of the applicator work head are properly adjusted, no evidence of spiral application is noticeable on the paint film. It is also of importance that the timing be such that rotation of the work piece is not so high that paint throw-off takes place. This is in part also controlled by the consistency of the paint 131 in the pan 132.

Two or more colour bands can be applied to the work piece at the same time at one applicator head, the bands being placed as close together as the centres of the applicator assemblies will allow in conjunction with horizontal travel of the applicators. The machine can also be set up to apply extra wide bands of the same colour on the work piece. This is accomplished by staggering the positions of the applicator assembly on one applicator work head relative to the position of the applicator assembly on the next adjacent head. With this arrangement the blending of one banding applied at one head with that applied at an adjacent head, is such that no joining mark is visible. It also follows that extra wide bands of the same or different colours can be applied spaced apart from each other, this being controlled by the number of applicator work heads that are fitted to the machine.

From the above description of the banding machine and the method of operating it, it will be seen that an infinite variety in the number of bands and width of bands can be applied to a work piece, varying from that applied by a single revolution contact of the work piece with the applicator disc, to that applied by maximum revolution contact of the work piece with the applicator disc supplemented by succeeding stage contact, by having the machine properly set up before commencing operations. In addition, a wide variety of colour banding can be accomplished in the same manner, as for every width of band that can be applied to the work, that band can vary in colour without disturbing the machine setting, for it is a simple matter to change one colour pan 132 for a pan having a different colour. Also, by staggering the applicator discs in one applicator work head relative to the others, various colours can be applied practically touching each other.

What I claim is:

1. In a ceramic paint banding machine, a stationary frame, a rotating member journaled in said stationary frame, a series of work-heads mounted on said rotating member, vacuum means connected to said work-heads adapted to hold a work piece on said work-heads during the banding operation, drive means including a Geneva

type drive rotating said rotating member intermittently in stages corresponding in number with said work-heads, a drive including a friction disc engaging with and rotating said work-heads, cam means holding said work-heads out of engagement with said friction disc during a partial rotation of said rotating member, paint applicators mounted for both vertical and horizontal movement on said stationary frame and drive means reciprocating said paint applicators vertically into and out of engagement with the work piece mounted on said work-heads and to reciprocate said paint applicators horizontally with respect to said work piece to apply bands of paint thereon when the work-heads are held stationary during their intermittent rotation.

2. In a ceramic paint banding machine, a stationary frame, a rotating member journalled in said stationary frame, a series of work-heads mounted on said rotating member, vacuum means connected to said work-heads holding a work piece on said work-heads during the banding operation, drive means including a Geneva type drive rotating said rotating member intermittently in stages corresponding in number with said work-heads, a drive including a friction disc engaging with and rotating said work-heads, cam means secured to said stationary frame, a series of plunger rods mounted on said rotating member and in contact with said cam means, said plunger rods holding said work-heads out of engagement with said friction disc during a partial rotation of said rotating member, paint applicators mounted for both vertical and horizontal movement on said stationary frame and drive means reciprocating said paint applicators vertically into and out of engagement with the work piece mounted on said work-heads and to reciprocate said paint applicators horizontally with respect to said work piece, to apply bands of paint thereon when the work-heads are held stationary during their intermittent rotation.

3. In a ceramic paint banding machine, a stationary frame, a rotating member journalled in said stationary frame, said rotating member forming a sealed vacuum chamber, a series of work-heads mounted on said rotating member, each work-head adapted to support a work piece to be banded, a vacuum connection between said vacuum chamber and each work-head, a valve in each of said vacuum connections, cam means on said stationary frame engaging with and closing said valves and thereby cutting off the vacuum to said work-heads during a partial rotation of said rotating member, drive means including a Geneva type drive rotating said rotating member intermittently in stages corresponding in number with said work-heads, a drive including a friction disc engaging with and rotating said work-heads, cam means secured to said stationary frame a series of plunger rods mounted on said rotating member and in contact with said cam means, said plunger rods holding said work-heads out of engagement with said friction disc during a partial rotation of said rotating member, paint applicators mounted for both vertical and horizontal movement on said stationary frame, and drive means reciprocating said paint applicators vertically into and out of engagement with the work pieces mounted on said work-heads and to reciprocate said paint applicators horizontally with respect to said work pieces when the work pieces are being rotated to apply bands of paint thereon.

4. In a ceramic paint banding machine, a stationary frame, a rotating member journalled in said stationary frame, said rotating member forming a sealed vacuum chamber, a series of work-heads mounted on said rotating member, each work-head adapted to support a work-piece to be banded, a vacuum connection between said vacuum chamber and each work-head, a valve in each of said vacuum connections, cam means on said stationary frame engaging with and closing said valves and thereby cutting off the vacuum to the work-heads during a partial rotation of said rotating member, drive

means including a Geneva type drive rotating said rotating member intermittently in stages corresponding in number with said work-heads, a drive including a friction disc engaging with and rotating said work-heads, cam means secured to said stationary frame a series of plunger rods mounted on said rotating member and in contact with said cam means, said plunger rods holding said work-heads out of engagement with said friction disc during a partial rotation of said rotating member, paint applicators mounted for both vertical and horizontal movement on said stationary frame, drive means reciprocating said paint applicators vertically into and out of engagement with the work pieces mounted on said work-heads and to reciprocate said paint applicators horizontally with respect to said work pieces when the work pieces are being rotated, and cam means operatively connected with said latter drive means controlling the period of engagement of said paint applicators with the work piece.

5. In a ceramic paint banding machine, a stationary frame, a rotating member journalled on said stationary frame, said rotating member forming a sealed vacuum chamber, a series of work-heads mounted on said rotating member, each work-head adapted to support a work piece to be banded, a vacuum connection between said vacuum chamber and each work-head, a valve in each of said vacuum connections, cam means on said stationary frame engaging with and closing said valves and thereby cutting off the vacuum to the work-heads during a partial rotation of said rotating member, drive means including a Geneva type drive rotating said rotating member intermittently in stages corresponding in number with said work-heads, a drive including a friction disc engaging with and rotating said work-heads, cam means secured to said stationary frame a series of plunger rods mounted on said rotating member and in contact with said cam means, said plunger rods holding said work-heads out of engagement with said friction disc during a partial rotation of said rotating member, paint applicators mounted for both vertical and horizontal movement on said stationary frame, drive means including a cam reciprocating said paint applicators vertically into and out of engagement with the work pieces mounted in said work-heads, a cam operatively connected with said latter drive reciprocating said paint applicators horizontally with respect to said work pieces, said latter two cams being co-ordinated to control the period of time the paint applicators are in contact with the rotating work pieces and the width of paint band applied thereto.

6. In a ceramic paint banding machine, a stationary frame, a rotating member journalled in said stationary frame, said rotating member forming a sealed vacuum chamber, a series of pivoted work-heads mounted on said rotating member, each work-head adapted to support a work piece to be banded, a vacuum connection between said vacuum chamber and each work-head, a valve in each of said vacuum connections, cam means on said stationary frame engaging with and closing said valves and thereby cut off the vacuum to the work-heads during a partial rotation of said rotary member, drive means including a Geneva type drive rotating said rotating member intermittently in stages corresponding in number with said work-heads, a drive including a friction disc engaging with and rotating said work-heads, cam means secured to said stationary frame a series of plunger rods mounted on said rotating member and in contact with said cam means, said plunger rods pivoting said work-heads and holding them out of engagement with said friction disc during partial rotation of said rotating member, paint applicators mounted for both vertical and horizontal movement on said stationary frame, drive means including a cam reciprocating said paint applicators vertically into and out of engagement with the work pieces mounted on said work-heads, a cam operatively connected with said latter drive reciprocating said paint applicators hor-

izontally with respect to said work pieces, said latter two cams being co-ordinated to control the period of time the paint applicators are in contact with the rotating work pieces and the width of band applied thereto.

7. In a ceramic paint banding machine, a stationary frame, a cover plate on said stationary frame, a rotating member journalled in said stationary frame, said rotating member resting on said cover plate and sealed therewith to form a vacuum chamber, a series of pivoted work-heads mounted in spaced relationship on said rotating member and disposed radially with respect to the axis of the rotating member, each work head adapted to support a work-piece to be banded a shaft rotatably mounted in each of said work-heads, each of said shafts having a friction drive wheel at its inner end and a vacuum chuck on its outer end, a vacuum connection between said vacuum chamber and each work-head, a valve in each of said vacuum connections, an arcuate cam on said cover plate, said arcuate cam closing said valves to cut off the vacuum to said vacuum chuck during partial rotation of said rotary member, drive means including a Geneva type drive rotating said rotating member intermittently in stages corresponding in number with said work-heads, a drive including a friction disc engaging with said work-head shafts through said friction drive wheels, arcuate cam means secured to said stationary frame a series of plunger rods mounted on said rotating member and in contact with said cam means, said plunger rods pivoting said work-heads to disengage their shafts from said friction disc during partial rotation of said rotating member, paint applicators mounted for both vertical and horizontal movement on said stationary frame, drive means including a cam reciprocating said paint applicators vertically into and out of engagement with the work pieces mounted on said vacuum chucks, a cam operatively connected with said latter drive reciprocating said paint applicators horizontally with respect to said work pieces, said latter two cams being coordinated to control the period of time the paint applicators are in contact with the rotating work pieces and the width of band applied thereto.

8. In a ceramic paint banding machine, a stationary frame, a cover plate on said stationary frame, a rotating member journalled in said stationary frame, said rotating member resting on said cover plate and sealed therewith to form a vacuum chamber, a series of pivoted work-heads mounted in spaced relationship on said rotating member and disposed radially with respect to the axis of the rotating member, each work head adapted to support a work-piece to be banded a shaft rotatably mounted in each of said work-heads, each of said shafts having a friction drive wheel at its inner end and a vacuum chuck on its outer end, said vacuum chuck including a valve spring held in its closed position, and movable into its open position when a work-piece is fitted on the work head, a vacuum connection between said vacuum chamber and each work-head and through said shaft to said vacuum chuck, a valve in each of said vacuum connections at the outlet from said vacuum chamber, an arcuate cam on said cover plate, said arcuate cam closing said latter valves to cut off the vacuum to said vacuum chuck during partial rotation of said rotary member, drive means including a Geneva type drive rotating said rotating member intermittently in stages corresponding in number with said work-heads, a drive including a friction disc engaging with said work-head shafts through engagement with said friction drive wheels, arcuate cam means secured to said stationary frame a series of plunger rods mounted on said rotating member and in contact with said cam means, said plunger rods pivoting said work-heads to disengage their shafts from said friction disc during partial rotation of said rotating member, paint applicators mounted for both vertical and horizontal

movement on said stationary frame, drive means including a cam reciprocating said paint applicators vertically into and out of engagement with the work pieces mounted on said vacuum chucks, a cam operably connected with said latter drive reciprocating said paint applicators horizontally with respect to said work pieces, said latter two cams being co-ordinated to control the period of time the paint applicators are in contact with the rotating work pieces and the width of the band applied thereto.

9. In a ceramic paint banding machine, a stationary frame, a rotating member journalled in said stationary frame, a series of work-heads mounted on said rotating member each of said work-heads comprising a cylinder, the axis of which is disposed radially with respect to the axis of rotation of said rotating member, a shaft rotatably journalled in said cylinder and extending therebeyond at either end, said shafts having a friction drive wheel at their inner end and a flange at their outer end, a vacuum passage in said shaft open at one end to the interior of said cylinder and to the outer surface of the shaft adjacent its end flange, a vacuum chuck on the end of said shaft, said chuck forming a valve normally sealing the outer end of said vacuum passage and on the application of a work piece to the chuck moving said valve to unseal said vacuum passage to secure the work piece to the chuck by vacuum, vacuum means connected with said cylinder and with said chuck through said vacuum passage, drive means rotating said rotating member intermittently in stages corresponding in number with said work-heads, a drive including a friction disc engaging with and rotating the friction drive wheels of said work head shafts, paint applicators mounted for both vertical and horizontal movement on said stationary frame, and drive means reciprocating said paint applicators vertically into and out of engagement with the work pieces on said chucks and reciprocating said paint applicators horizontally with respect to said work pieces to apply bands of paint thereto when the work-heads are held stationary during their intermittent rotation.

10. In a ceramic paint banding machine, a stationary frame, a rotating member journalled in said stationary frame, a series of work-heads mounted on said rotating member, each of said work-heads comprising a cylinder, the axis of which is disposed radially with respect to the axis of rotation of said rotating member, a shaft rotatably journalled in each of said cylinders and extending beyond the cylinders at either end, said shafts having a friction drive disc at their inner end and a flange at their outer end, an axial bore to said shaft open at one end to the interior of said cylinder and to the outer surface of the shaft adjacent their end flange forming a vacuum passage, a vacuum chuck on the outer end of said shaft, said chuck comprising a work-piece sealing washer spaced inwardly of said shaft end flange, a pair of friction discs slidably mounted on said shaft, a spring between the inner of said friction discs and said sealing washer, a spring between said pair of friction discs, said springs normally holding the outer of said friction discs in sealing position over the outer end of the axial bore of said shaft, vacuum means connected with said cylinders and through the axial bore of the shafts with said vacuum chuck, said vacuum means holding a work piece against said sealing face when the friction discs of the chuck are displaced by the work piece to expose the vacuum passage in the shaft to the interior of the work piece, drive means rotating said rotating member intermittently in stages corresponding in number with said work-heads, a drive including a friction disc engaging with and rotating the friction drive wheels of said work head shafts, paint applicators mounted for both vertical and horizontal movement on said stationary frame and drive means reciprocating said paint

applicators vertically into and out of engagement with the work piece on said chucks and to reciprocate said paint applicators horizontally with respect to said work pieces to apply bands of paint thereon when the work heads are held stationary during their intermittent rotation.

11. In a ceramic paint banding machine, a stationary frame, a rotating member journaled in said stationary frame, a series of work-heads mounted on said rotating member, each work-head adapted to support a work-piece to be banded, a vacuum connection to each of said work-heads, a valve in each of said vacuum connections, cam means on said stationary frame engaging with and closing said valves and thereby cutting off the vacuum supply to said work-heads during a partial rotation of said rotating member, drive means including a Geneva type drive rotating said rotating member intermittently in stages corresponding in number with said work-heads, a drive including a friction disc engaging with and rotating said work-heads, cam means holding said work-heads out of engagement with said friction drive during partial rotation of said rotating member, paint applicators mounted for both vertical and horizontal movement on said stationary frame, drive means including a cam reciprocating said paint applicators vertically into and out of engagement with the work pieces mounted on said work-heads, a cam operatively connected with said latter drive means reciprocating said paint applicators horizontally with respect to said work pieces, said latter two cams being co-ordinated to control the period of time the paint applicators are in contact with the work pieces and the width of the band applied thereto.

12. In a ceramic paint banding machine, a stationary frame, a rotating member journaled in said stationary frame, a series of work-heads mounted on said rotating member, a rotatable vacuum chuck associated with each of said work-heads adapted to hold a work piece when vacuum is applied to the chuck, a vacuum connection to each of said chucks through said work-heads, a valve in each of said vacuum connections, cam means on said stationary frame engaging with and closing said valves and thereby cutting off the vacuum supply to said work-heads during a partial rotation of said rotating member, drive means including a Geneva type drive rotating said rotating member intermittently in stages corresponding in number with said work-heads, a drive including a friction disc engaging with and rotating said work-heads, cam means holding said work-heads out of engagement with said friction drive during partial rotation of said rotating member, paint applicators including a paint reservoir mounted for both vertical and horizontal movement on said stationary frame, a disc in said reservoir, said disc being rotated in the paint reservoir when brought into contact with the rotating work piece on the vacuum chuck, a rotary drive shaft, including a cam rotated by said drive shaft reciprocating said paint applicators vertically into and out of engagement with the work pieces mounted on said vacuum chucks, a cam rotated by said drive shaft reciprocating said paint applicators horizontally with respect to said work pieces, said latter two cams being co-ordinated to control the period of time the paint applicators are in contact with the work pieces and the width of band applied thereto.

13. In a ceramic paint banding machine as set forth in claim 12, wherein the disc of the paint applicators are spring mounted to apply a degree of pressure of the disc against the work piece.

14. In a ceramic paint banding machine as set forth in claim 13, wherein the spring mounting of the disc is adjustable to vary the contact pressure of the disc on the work piece.

15. In a ceramic paint banding machine as set forth in claim 14 wherein the cams controlling the vertical recipro-

cation of the paint applicators are adjustable to vary the period of time in which the applicator discs are in contact with the work pieces.

16. In a ceramic paint banding machine as set forth in claim 15, wherein the cams controlling the vertical reciprocation of the paint applicators are in two parts radially adjustable with each other to vary the length of the cam surface holding the applicator disc in contact with the work piece.
17. In a ceramic paint banding machine as set forth in claim 12, wherein the cam controlling the horizontal reciprocation of the paint applicator contacts a roller mounted on a horizontally slideable bracket the said bracket being spring held to hold the roller against the said cam.
18. In a ceramic paint banding machine as set forth in claim 17, wherein the paint reservoir is mounted on a platform vertically slideable on the horizontally slideable bracket.
19. In a ceramic paint banding machine as set forth in claim 18, wherein the drive means for the cams controlling the operation of the paint applicators includes a shaft journaled in the stationary frame of the machine and a shaft journaled in the horizontally sliding bracket, the said shafts being splined together.
20. In a ceramic paint banding machine, a stationary frame, a rotating member journaled in said stationary frame, said rotating member forming a sealed vacuum chamber, a series of pivoted work-heads mounted on said rotating members, a rotatable vacuum chuck associated with each of said work-heads adapted to hold a work-piece when vacuum is applied to the chuck, a vacuum connection from said vacuum chamber to each of said vacuum chucks through said work-heads, valves in said vacuum chamber controlling the said vacuum connections, said valve comprising a cylinder having an inlet port and an atmospheric port, ported sleeve valves each within said cylinder, a spring normally holding said sleeve in position to allow vacuum to pass through said ported sleeve from the vacuum chamber through the connection to the vacuum chuck, cam means on said stationary frame engaging with and displacing said ported sleeve to cut off the vacuum to said vacuum chuck and to allow atmospheric pressure to fill said vacuum connection to the chuck during partial rotation of said rotating member, drive means rotating said rotating member intermittently in stages corresponding in number with said work-heads, a drive including a friction disc engaging with said work-heads to rotate said chucks, cam means holding said work-heads out of engagement with said friction drive during partial rotation of said rotating member, paint applicators mounted for both vertical and horizontal movement on said stationary frame, drive means including a cam reciprocating said paint applicators vertically into and out of engagement with the work pieces mounted on said chucks, and a cam operatively connected with said latter drive reciprocating said paint applicators horizontally with respect to said work pieces, said latter two cams being co-ordinated to control the period of time the paint applicators are in contact with the rotating work pieces and the width of band applied thereto.
21. In a ceramic paint banding machine, as set forth in claim 20, wherein springs normally hold the work-heads in engagement with the friction drive for rotation of the vacuum chuck.
22. In a ceramic paint banding machine as set forth in claim 21, wherein an adjustable stop between the rotating member and the work-heads adjusts the pivotal position of the work-heads to bring the under side of the work-piece parallel with the horizontal travel of the paint applicator.

23. In a ceramic paint banding machine as set forth in claim 22, in which the vertical position of the driven friction disc in relation to the work-heads can be adjusted in conjunction with the adjustable stops for more accurate setting of the work pieces with respect to the paint applicators.
